(57) CLAIM

The ornamental design for a heating ignition device, as shown and described.

DESCRIPTION

FIG. 1 is a perspective view of a heating ignition device showing our new design;

FIG. 2 is a left view thereof;

FIG. 3 is a right view thereof;

FIG. 4 is a top view thereof;

FIG. 5 is a bottom view thereof;

FIG. 6 is a front view thereof;

FIG. 7 is a rear view thereof;

FIG. 8 is an enlarged view of Section A of FIG. 1; and,
FIG. 9 is an enlarged view of Section B of FIG. 1.

The broken lines in FIGS. 1, 8 and 9 represent boundaries of the enlarged portions and form no part of the claimed design. The bar portion of the heating ignition device is shown broken away in the figures to indicate that no particular length is claimed.
